UNITED STATES PATENT OFFICE

2,572,271

MOTOR DRIVEN HONING AND STROPPING DEVICE FOR RAZORS

Paul R. McCauley, Kansas City, Mo.

Application July 29, 1948, Serial No. 41,209

3 Claims. (Cl. 51—153)

1

This invention relates to a razor and motor driven honing and stropping device therefor and more particularly to the razor having a removable permanent blade and a motor driven device adapted to receive said blade for selective reciprocating motion during which the sides of the edge of the blade are automatically alternately presented to a stropping or honing surface at the proper angle to restore the cutting edge of said blade.

The objects of the invention are to provide a permanent razor blade having spring pressed locking devices adapting said blade for application to either a razor for use or a blade holder in a stropping and/or honing device; to provide a motor driven device adapted to receive said blade and impart motion thereto for either honing or stropping and which may be readily changed from one to the other; to provide apparatus for automatically and alternately presenting the sides of the edge of a razor blade to a stropping and/or honing surface at the proper angle while imparting a reciprocating arcuate stroke to said blade relative to said surfaces; to provide for reversing the direction of the stroking movement of the blade and lifting of the blade edge from engagement with the stropping and/or honing surface before such reversal thus avoiding damage to the blade and strop; to provide an arcuate motion to the blade holder with the edge of the blade parallel thereto and trailing therefrom whereby the effective relative movement of the side of the blade edge and the surface contacted thereby is substantially angular to said edge; to provide a motor driven transmission mechanism for moving the blade holder in an arc and reversing said motion; to provide a complete self-contained blade honing and stropping device of simple structure, light in weight, adapted for economical manufacture; and to provide an apparatus of this character which is easily transported as in a person's luggage and capable of being quickly and efficiently used for restoring the cutting edge of the razor blade.

In accomplishing these and other objects of the present invention, I have provided an improved detail structure, the preferred forms of which are illustrated in the accompanying drawings, wherein:

Fig. 1 is a perspective view of the upper portion of the honing and stropping device, portions being broken away to better illustrate the structure.

Fig. 2 is a vertical sectional view through the blade honing and stropping device with the cover applied thereto as for transporting same.

Fig. 3 is a plan view of the motor and trans-

2

mission housing with the sharpening assembly removed therefrom.

Fig. 4 is a plan view of the honing and stropping device with the cover removed therefrom.

5 Fig. 5 is a transverse sectional view through the blade holder illustrating the position of the respective parts as the holder approaches the end of its stroke.

10 Fig. 6 is a view similar to Fig. 5 with the blade holder substantially at the end of its stroke.

Fig. 7 is a view similar to Fig. 5 illustrating the position of the blade at the beginning of the return stroke wherein said blade is rotated to the opposite side of the blade holder.

15 Fig. 8 is a perspective view of a razor and blade shown in disassembled relation.

Fig. 9 is a side elevation of the razor and blade applied thereto.

20 Fig. 10 is an elevation of the razor blade, portions being broken to show the locking devices therein.

Fig. 11 is an end elevation of the blade.

Fig. 12 is a perspective view of the end of the blade holder and the blade shown in disassembled

25 spaced relation.

Fig. 13 is a vertical sectional view through the blade holder.

Fig. 14 is a transverse sectional view through the blade holder on the line 14—14, Fig. 13.

30 Referring more in detail to the drawings:

1 designates a razor blade having hollow ground sides 2 forming a cutting edge 3. The hollow ground sides are so arranged that the blade is substantially wedge shape in cross section, the 35 sides generally tapering from the cutting edge 3 to the rear edge 4 which is flat, the blade being relatively thick at that portion. A cylindrical socket 5 extends into the center of the rear edge of the blade towards the cutting edge, said socket 40 preferably being perpendicular to the cutting edge of said blade. Spaced from the rear edge 4 and extending through the blade from side to side thereof is a bore 6, said bore being of the same diameter as the socket 5 and in alignment with and intersecting said socket. Arranged longitudinally of the blade and perpendicular to the axes of the socket 5 and bore 6 is a bore 7, axis of which passes through the point of intersection of the axes of the socket 5 and bore 6. Coaxial 45 with the bore 7 are counterbores 8 extending inwardly from the end edges 9 of said blade and terminating in shoulders 10 spaced from the socket 5. Slidably mounted in the bore 7 are plungers 11 adapted to extend into the socket 5, heads 12 on said plungers engaging the shoulders 10 to limit longitudinal movement of said plungers. The ends of the counterbores 8 are provided

with plugs 13 closing the counterbores and springs 14 are arranged between said plugs and the heads 12 on the plungers 11 whereby the ends of said springs engage same to apply pressure to the head 12 tending to force the plungers 11 into the intersecting portions of the bore 6 and socket 5.

This structure of the blades adapts same to be applied to a razor 15 by insertion of a pin 16 carried thereby into the bore 6, said pin having recesses 17 adapted to be engaged by the ends of the plungers 11 to secure said blades on said pin whereby the side face towards the handle 18 of the razor engages a bracket 19 on which the pin 16 is mounted. The bracket 19 extends laterally of the pin 16 and terminates in a curved portion 20 having a recess 21 adapted to receive a head 22 of a razor guard 23, said head being semi-circular in cross section and having a flat face 24 adjacent the pin 16 adapted to engage the flat rear edge 4 of the razor blade. The guard includes a U-shape member 25, the legs of which are secured to the flat portion 24 of the head 22 adjacent the ends thereof, said U-shape member being of such size that the bar portion 26 connecting the legs will engage the razor blade adjacent the cutting edge and the face of a user to prevent cutting of the skin over which the razor moves.

Mounted on the bracket 19 and extending away from the razor blade is a shank 27 terminating in the handle 18, said handle being hollow to receive a battery or the like 28, which is held in place by a cap 29 and has suitable electrical connections with a light 30 adapted to illuminate the surface to be shaved as illustrated in Fig. 9. With this type of razor and blade, the arrangement of the springs 14, plungers 11 and bores in the blade together with the pin 16 on the razor provides a snap-on effect for placing the blade on the razor. Obviously, the blade is of the permanent type and since it is dulled by use, it must be honed and stropped to restore the cutting edge thereof. This operation is done on a motor-driven strop and honing device 31 now to be described.

The honing and stropping device consists of a lower housing 32 preferably having a vertical cylindrical wall 33 terminating at its lower edge in a flange 34 having an annular recess 35 therein to receive a bottom member 36 adapted to form a closure of the motor chamber in said housing. Spaced from the lower end of the wall 33 and preferably integral therewith is a horizontal partition 38 forming the upper wall of the motor chamber 37, the wall 33 extends upwardly from the partition 38 and is recessed as at 39, adjacent the upper end for mounting blade-sharpening equipment as later described.

A motor 40 is located in a motor chamber and carried by a mounting bracket 41 secured by suitable fastening devices such as bolts 42 to the partition 38, said motor having suitable electrical connections adapted to be controlled by a suitable switch not shown. The shaft 43 of the motor extends outwardly from one end thereof. The outer end of said shaft 43 being supported by a bracket 44 which is secured by screws or the like 45 to bosses 46 depending from the partition 38. Fixed to the shaft 43 is a worm 47 arranged to mesh with a gear 48 fixed to a vertically arranged shaft 49 rotatably mounted in bearings 50 and 51 carried by the bottom member 36 and the partition 38. The worm gear shaft 49 extends upwardly from the partition 38 and fixed thereon is an arm 52 adapted to be ro-

tated about the axes of the shaft 49. The outer end of the arm 52 carries a pin 53 pivotally mounting one end of a connecting rod 54, the opposite end of which is preferably rotatably connected to a pin 55 carried adjacent the periphery of an oscillating gear 56 rotatably mounted on a shaft 57 which extends upwardly from the partition 38.

The oscillating gear 56 has teeth 58 on its periphery engaging teeth of a pinion 59 fixed on a pinion shaft 60, the lower end of which is rotatably mounted in a bearing recess 61 in the upper face of the partition 38. The pinion shaft 60 extends upwardly from the pinion and is provided with a slot 62 adapted to engage a rib 63 extending across a bore 64 in a hub 65 on an arm assembly 66. The hub 65 is rotatably mounted in a bore 67 in a plate 68 seated on the seat 39 at the upper end of the housing wall, said plate 20 being suitably secured on said seat as by screws 69 threaded into threaded holes 70 in bosses on the partition 38. The lower end of the hub 65 rests on the upper end of a bushing 71 located in the bore 67 and sleeved over the pinion shaft 25 60 to form a bearing therefor.

The plate 68 is preferably of the same outer diameter as the housing wall 33 and the upper face 73 of said plate being provided with a circular recess 74, the outer peripheral edge 75 of which is spaced inwardly from the outer periphery of the plate 68. The radial width of said recess is substantially the same as the length of the cutting edge of the blade 1. Located in the recess is stropping material 77 and honing material 78 suitably secured as by cement in the recess whereby the stropping and honing surfaces are substantially flush with the flat upper space 73 of the plate 68. The honing material is so arranged that the inner edges form a complete half circle and terminates at diametrical points 79 and 80, the side edges 81 diverging outwardly in such a manner that the arcuate lengths at the outer edge is the same as the arcuate lengths at the inner edge. The stropping material 77 fills the remainder of the recess and is suitably sloped as at 82 to relieve the outer or end portions opposite the honing surface and is of such size that the arcuate lengths adjacent the outer periphery is equal to the arcuate lengths of the inner periphery. This arrangement is such that all portions of the blade edge is in contact with either the stropping surface or honing surface for an equal distance thereby giving the same stropping or honing effect on said cutting edge at each end of the blade. The upper face 73 of the plate 68 is also provided with a groove 83 of smaller diameter than the inner portion of the recess 75 and secured in said groove are cams 84 and 85 having high portions 86 and downwardly and outwardly sloping sides 87. The high portions of the cams are diametrically opposed and in alignment with the points 79 and 80 for controlling operation of the blade holding device as later described.

Sleeved over the upper portion of the wall 33 is a cylindrical wall 88 of an upper housing 89 which is secured to the lower housing by means of screws 90 inserted in threaded bores 91 in the upper portion of the wall 33. The wall 88 extends upwardly above the plate 68 and terminates in an inwardly directed flange 92, the lower surface 93 of which cooperates with the outer portion of the upper face 73 of the plate 68 to form a track for rollers 94 mounted on the outer ends of the arm assembly 66. The inner portion of the wall face 93 of the frame 92 is grooved as at 95

to receive a ring gear 96 having downwardly directed teeth 97, said gear 96 being suitably secured in the groove as by cementing.

The arm assembly 66 consists of oppositely directed hollow arms 98 integral with the hub 65 and having bearing bushings 99 mounted therein, said bushings have bores 100 to rotatably mount pins 101 therein. The pins 101 extend beyond the inner end of said bushings and have lock rings 102 adjacent said bushings for securing said pins against the outward movement in the bushings. The pins 101 are parts of arm shafts 103 of larger diameter than the pin whereby the inner ends 104 of said shafts engage the outer ends of the bushings to cooperate with lock rings to prevent longitudinal movement of said shaft. Spaced from the ends 104 of the shafts 103, a distance substantially equal to the length of the blade 1 are enlarged portions 105, the inner edges 106 of which are adapted to engage the outer ends of a shell 107 frictionally engaging the shafts between the bearing bushing 99 and enlarged portion 105. The arm shafts 103 are provided with reduced portions 108 projecting beyond the enlarged portion 105, said reduced portions having pinion gears 109 secured to the outer ends thereof and in position for the teeth of the pinion gear to engage the teeth 97 of the ring gear 96. The reduced portions 108 of the arm shafts 103 are also provided with axial bores 110 for rotatably mounting roller pins 111 on which are fixed the rollers 94 whereby said rollers will engage the track formed by the upper face 73 of the plate 68 and the lower face 93 of the flange 92.

The shells 107 are preferably formed of resilient material such as spring steel bent in a cylindrical shape and of such size as to require expansion of said shells when they are placed over the arm shafts 103 thereby providing friction between the shells and said arm shafts. The edges 112 of said shells being spaced as illustrated in Fig. 14 to facilitate mounting said shells on the arm shafts. Arranged midway between the ends of the shells and projecting outwardly therefrom opposite to the spaced edges are pins 113 of such size as to be a sliding fit in the socket 5 of the razor blade. The pins 113 are preferably arranged in apertures 114 in said shells whereby the inner ends of the pins project inwardly of said shells, the arm shafts being provided with reduced diameters as at 115 to accommodate the inner ends of said pins. Each of the pins is also provided with recesses 116 in the sides thereof suitably placed to receive the ends of the pins 11 in the razor blade when a blade is supplied thereto with the pin 113 engaged in the socket 5 and the rear edge 4 of the blade contacting the periphery of the shell 107. Mounted at the inner ends of the shells and in alignment with the groove 83 in the plate 68 are arrester followers 117, consisting of arcuate members 118 secured to said shells as by welding and extending from the edges 112 of said shells to points 119 spaced substantially the thickness of the rear edge of the blade 1 and terminating in outwardly directed portions 120 adapted to engage in the groove 83 to arrest movement of the blade as later described.

When the stropping and honing device is not in use, the upper portion is preferably covered by a cover member 121 of substantially the same outer diameter as the upper housing 89 and adapted to seat on the flange 92. Said cover 121 having spring clips 122 secured thereto in opposed relation and adapted to extend down-

wardly over the edge of the cover and upper portions of the upper housing whereby shoulders 123 of said clip engage in recesses 124 in the upper housing to secure said cover thereon.

5 In operating a device such as described for restoring the edge of the blade 1 when same has been dulled by use, the shoulders 123 are released from the recesses 124 whereby the cover is removed from the upper housing to provide access 10 to the arm assembly for mounting the blade thereon.

It is preferable to have two blades, however, the device will operate entirely satisfactory with only one blade. The blade is removed from the 15 razor and if it is desirable to hone said blade, it is placed on the portion of the arm assembly operating over the honing surface 78 by inserting the pin 113 thereon into the socket 5 until the 20 ends of the pins 11 engage in the recesses 116 to secure on the blade to the shell over said honing surface. The device is then connected to an electric circuit to energize the motor which 25 rotates the shaft 43 and worm 47 to drive the worm gear 48 and affect rotation of the shaft 49, thereby rotating the arm 52 to affect the reciprocation of the connecting rod 54. This in turn operates the gear 56 to actuate the pinion 59. The ratio of the diameters of the operating 30 gears and the pinions being such that the pinion will oscillate approximately 180°. Oscillation of the pinion 59 drives the shaft 60 to move the arm assembly 66 through an arc of 180°. The pin 113 and shell 107 are so arranged from the 35 arm shaft whereby when the arm is being moved the blade mounted on the pin trails behind the arm. The arm is held substantially in alignment, that is said arm operates in a plane parallel with the upper face 73 of the plate 68 through contact of the roller 94 with the surface 93 of the 40 flange 92 and the upper surface 73 of the plate 68. The engagement of the roller also maintains engagement of the teeth of the pinion gear 109 with the teeth 97 of the ring gear 96. As the arm is oscillated in an arcuate path, the pinion gear is rotated by the ring gear to rotate the arm shaft in such a manner as to tend to rotate the pin 113 and the blade thereon downwardly 45 against the honing surface due to frictional engagement of the shell on the arm shaft, which friction applies a force to the blade to maintain engagement of the side of the edge thereof with the honing surface.

As the axis of the arm assembly approaches a 50 vertical plane through the points 79 and 80 and the high points of the cams 84 and 85, the end 120 of an arrester follower 117 in the groove 83 engages the sloping surface 87 of one of the cams. This applies a force tending to resist the friction between the shell and the arm shaft thereby effecting rotation of the blade in the opposite direction to the direction of the rotation of the pinion gear. When the axis of the arm assembly is in alignment with high point of the cam, the pin 53 and the arm 52 passes dead center between the worm gear shaft 49 and the pin 55 on the oscillating gear 56 thereby starting the arm assembly in the opposite direction.

As soon as the arm assembly starts moving in the opposite direction, the engagement of the pinion gear with the ring gear rotates said pinion gear in the opposite direction thereby applying a rotating force to the shell, lifting said blade and turning same whereby it again trails behind the arm assembly as shown in Fig. 7 to provide a honing action on the other side of the blade edge.

This reversal of movement is continued with the blade being turned at the end of each stroke to maintain all contact between the blade edge and the honing surface at such time as when the blade is trailing the arm and as shown in Fig. 4 the edge of the blade is parallel to the arm assembly whereby the arcuate movement imparted thereto affects a sliding contact between the sides of the blade edge and the honing surface which is substantially angularly of the blade edge. This operating movement is continued until the blade is properly honed, the inner portion of the edge receiving the same honing action as the outer portion due to the fact that the arcuate length of all portions of said surface contacted by the blade are the same length.

After the blade is suitably honed, it is removed from the pin 113 and placed on the other pin 113 at the opposite end of the arm assembly. The device is again started to move the blade over the stropping surface 71 in the same manner as is operated over the honing surface. This operation being continued until the blade is properly stropped. The uniform pressure of the sides of the blade edge on the stropping or honing surface, the same arcuate travel during the engagement being applied to all portions of said blade edge, and the angular relative movement between the blade edge and the stropping or honing surface contacted thereby provide an efficient honing and stropping operation to restore the cutting edge of said blade.

After the blade has been suitably stropped, it is removed from the pin 113 and the cover 121 re-applied on the upper portion of the housing for storing said stropping device or placing same in the person's luggage as when traveling. The blade may then be applied to the razor by inserting the pin 16 on said razor into the bore 6 with the rear edge 4 in engagement with the flat surface 24 of the head of the guard. The blade is pressed downwardly until the pins 11 engage in the recesses 17 of the pin 16 at which time the side of the cutting edge of the blade engages the bar portion 26 of said guard. The razor is then ready for use and by operating a suitable switch the battery will energize the light 30 to provide illumination for the shaving operation as shown in Fig. 9.

What I claim and desire to secure by Letters Patent is:

1. A device for sharpening a razor blade comprising, a housing, a blade sharpening surface on the housing, an arm rotatably supported by the housing and spaced from the sharpening surface for arcuate movement in a plane above and parallel to said surface, means for effecting oscillatory movement of the arm in said plane, a shaft rotatably mounted in said arm and extending over the sharpening surface, a blade holder rotatably mounted on the shaft and frictionally engaging same for supporting a razor blade in alignment with the sharpening surface with the edge of said blade parallel to the arm and spaced therefrom, means for rotating said shaft in response to oscillatory movement of the arm to move a blade on said blade holder and apply pressure thereto forcing the blade into sharpening engagement with the sharpening surface in trailing relation to said arm, fingers on the blade holder, and cam means on the housing adjacent the respective ends of oscillation movement of the arm and engageable by the fingers for lifting the blade from the sharpening surface when the arm approaches the end of each oscillation.

2. A device for sharpening a razor blade comprising, a housing, a blade sharpening surface on the housing, an arm rotatably supported by the housing and spaced from the sharpening surface for arcuate movement in a plane above and parallel to said surface, a motor in the housing, means driven by the motor for effecting oscillatory movement of the arm in said plane, a shaft rotatably mounted in said arm and extending over the sharpening surface, a blade holder rotatably mounted on the shaft and frictionally engaging same for supporting a razor blade in alignment with the sharpening surface with the edge of said blade parallel to the arm and spaced therefrom, means for rotating said shaft in response to oscillatory movement of the arm to move a blade on said blade holder and apply pressure thereto forcing the blade into sharpening engagement with the sharpening surface in trailing relation to said arm, fingers on the blade holder, and cam means on the housing engageable by the fingers for lifting the blade from the sharpening surface when the arm approaches the end of each oscillation.
3. A device for sharpening a razor blade comprising, a housing, a blade sharpening surface on the housing, an arm rotatably supported by the housing and spaced from the sharpening surface for arcuate movement in a plane above and parallel to said surface, a motor in the housing, means driven by the motor for effecting oscillatory movement of the arm in said plane, a shaft rotatably mounted in said arm and extending over the sharpening surface, a blade holder rotatably mounted on the shaft and frictionally engaging same for supporting a razor blade in alignment with the sharpening surface with the edge of said blade parallel to the arm and spaced therefrom, a ring gear on the housing coaxial with the axis of rotation of the arm and spaced from the sharpening surface, a pinion gear fixed on the shaft and having engagement with the ring gear for rotating said shaft in response to oscillatory movement of the arm whereby the frictional engagement of the blade holder and shaft moves a blade on said blade holder and applies pressure thereto forcing the blade into sharpening engagement with the sharpening surface in trailing relation to said arm, fingers on the blade holder, and cam means on the housing adjacent the respective ends of the oscillation movement of the arm and engageable by the fingers for lifting the blade from the sharpening surface when the arm approaches the end of each oscillation.
